SPRAY ETCHER FOR WORK PIECES IN WHICH
THE WORK PIECES PROGRESS IN A SINGLE
DIRECTION FROM AN INPUT END TO AN OUT-
PUT END

Marshall I. Gurian, Tempe, and Peter F. J. Rose, Phoenix,
Ariz., assignors to Philip A. Hunt Chemical Corp.,
Palisades Park, N.J.

Filed June 9, 1975, Ser. No. 584,811

Term of patent 14 years

Int. Cl. D15—09

U.S. Cl. D55—1 R

FIG. 2

FIG. 1 is a top front left side perspective view of a spray etcher for work pieces in which the work pieces progress in a single direction from an input end to an output end showing our new design;

FIG. 2 is a top rear right side perspective view of said etcher; and

FIG. 3 is a bottom rear right side perspective view of said etcher.

We claim:

The ornamental design for a spray etcher for work pieces in which the work pieces progress in a single direction from an input end to an output end, substantially as shown.
